UNITED STATES PATENT OFFICE.

AUGUST F. CAMMANN, OF ST. LOUIS, MISSOURI.

HAT-TRAY.

SPECIFICATION forming part of Letters Patent No. 437,286, dated September 30, 1890.

Application filed January 18, 1890. Serial No. 337,343. (No model.)

To all whom it may concern:

Be it known that I, AUGUST F. CAMMANN, a citizen of the United States, residing at the city of St. Louis, in the State of Missouri, have invented a certain new and useful Improved Holder and Packing Device for Hats, of which the following is a full, clear, and exact description.

My invention relates to improved means of holding and packing hats, especially applicable to stiff hats, and has for its object to enable a series of hats to be packed and carried without injury, and also to be readily exhibited and repacked without trouble and delay.

It consists of a tray provided with one or more especially-constructed box-stays or hat-receptacles and in novel features of construction of said tray, which will be more fully described hereinafter.

In the accompanying drawings, Figure 1 represents a longitudinal sectional elevation of a closed trunk or packing-case containing my improved hat-holder; Fig. 2, a plan of the same with the lid of the trunk removed; Fig. 3, a front elevation thereof with the lid of the trunk thrown open and the upper series of hats in position for exhibition; Fig. 4, a longitudinal sectional elevation through one of the trays detached, taken on line 4 4 in Fig. 2, omitting the hats; and Fig. 5, a transverse section of the same, taken on line 5 5 in Fig. 2, like letters and numerals of reference denoting like parts in all the figures.

a represents a trunk or packing-case, within which are placed, one above the other, a series of trays b. Each tray b consists, preferably, of a floor 1, supporting four corner-posts 2, which are united externally at the ends and rear of the tray b by the top and bottom horizontal bars 3, and at the front of the tray b by a bottom horizontal bar 4 only, the external configuration of the tray so constructed being slightly less than the corresponding dimensions of the inside of the trunk a. On the floor 1 of each tray b are fixed at suitable distances apart box stays or receptacles c, each of which is preferably in the form of an oval box tapering slightly inward from its junction with the floor 1 to its upper open end, the edge whereof is of a concave form, (see particularly Figs. 4 and

5,) corresponding to that of the under side of the rim of a hat d, adjacent to its crown, whereby the opening of the receptacle may be expanded for the insertion of the hat, and, owing to the tapering form of the receptacle, will subsequently contract to grip and hold the hat, as well as to provide a uniform support which conforms to the contour of the brim of the hat. Through the floor 1 of each tray b are formed air-holes e for the escape of air, as hereinafter more particularly referred to.

Within the box-stays c are placed the crowns of the hats d, (see dotted lines, Fig. 1,) so that the rims of the hats d rest upon and overhang the upper edges of the box-stays c, as shown in Fig. 1.

The height of the corner-posts 2 of a tray b is such that when the floor 1 of a succeeding tray b rests upon their upper ends sufficient clearance is left between the under side of the said floor and the rims of the hats d within the first tray.

In operation, presuming that the trays b are removed from the trunk a and the hats d placed in the respective box-stays c, a tray b, with its hats d, is placed within the upper end of the trunk a, and, being let go, falls to the bottom of the latter, the air escaping from the trunk a beneath the descending tray b through the holes e in the floor 1, and thereby facilitating the descent of the tray b. A second tray b, with its hats d, is then placed within the trunk a and falls in like manner until its floor 1 rests upon the posts 2 of the preceding tray b, and so on throughout the entire series of trays b, when, the lid of the trunk a being closed, the latter, with its freight of hats, is ready for carriage. On opening the trunk a, the top series of hats d may be exhibited immediately by tilting them forward within their box-stays c, as shown in Fig. 3, and on lifting each tray b from the trunk a and placing it on a table each series of hats d may be in like manner exhibited on the shortest notice.

The great advantages of my invention are that the hats being confined within the box stays or receptacles c, adjacent to the respective floors 1 of the succeeding trays b, they cannot be knocked about and injured during their transportation within the trunk a. The

delay and injurious handling of the hats now experienced in unpacking and exhibiting are completely obviated, and the hats can be returned to stock without depreciation and loss.

5 Another advantage is that owing to the tapering of the receptacles ^c they are adapted for receiving varying styles of hats.

I claim as my invention—

1. In a packing-box for hats, a hat-receptacle having the form of a truncated cone resting on its base, the edges of the truncated portion being concave to increase the size of the opening for receiving the hat and to coact with the tapering form of the receptacle in 15 grasping and holding the hat when inserted, substantially as and for the purposes described.

2. In a hat-tray for packing-boxes, the combination, with a bottom, of one or more hat-receptacles secured to said bottom, a series of corner-posts on said bottom, and a top rail or bar arranged on three sides thereof, the whole forming a skeleton tray wherein the hat may be tilted for display, substantially as and for the purposes described.

In testimony whereof I have affixed my signature, in presence of two witnesses, this 9th day of January, 1890.

AUGUST F. CAMMANN.
